(57) **CLAIM**

The ornamental design for a table ornament, as shown and described.

DESCRIPTION

The file of this patent contains at least one photograph executed in color. Copies of this patent with color photograph(s) will be provided by the Office upon request and payment of the necessary fee.

FIG. 1 is a front, right and top perspective view of a table ornament, showing my design.

FIG. 2 is a front, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, left and top perspective view of the table ornament in another state.

FIG. 10 is a rear, right and top perspective view of the table ornament in another state.

FIG. 11 is an enlarged view of detail 11 in FIG. 1.

FIG. 12 is an enlarged view of detail 12 in FIG. 1.

FIG. 13 is an enlarged view of detail 13 in FIG. 1.

FIG. 14 is an enlarged view of detail 14 in FIG. 1.

FIG. 15 is an enlarged view of detail 15 in FIG. 1.

FIG. 16 is an enlarged view of detail 16 in FIG. 1; and,

FIG. 17 is an enlarged view of detail 17 in FIG. 2.

The broken lines in FIGS. 1-2 and 11-17 depict the boundaries of the enlargements that form no part of the claimed design.
